WHEELED EARTH SCRAPER

Filed June 6, 1925

3 Sheets-Sheet 3

UNITED STATES PATENT OFFICE.

JAMES M. BROOKS, OF ATLANTA, GEORGIA.

WHEELED EARTH SCRAPER.

Application filed June 6, 1925. Serial No. 35,325.

To all whom it may concern:

Be it known that I, JAMES M. BROOKS, a citizen of the United States of America, and a resident of Atlanta, county of Fulton, 5 and State of Georgia, have invented certain new and useful Improvements in Wheeled Earth Scrapers, of which the following is a full and clear specification.

The object of this invention is to simplify 10 the construction of this class of machines, so that they will be cheaper to build, less expensive to repair and keep in good working order, greatly more durable and easier to operate both as to loading and dumping.

15 In the drawing—

Fig. 1 is a side elevation with the near wheels removed, the scoop being raised from the ground in position for transportation, loaded or unloaded;

20 Fig. 2 is a view similar to Fig. 1, showing the scoop in position for loading;

Fig. 3 is a plan view of the device;

Fig. 4 is a detail sectional view on the line 4—4 of Figs. 1 and 5;

25 Fig. 5 is a detail sectional view on the line 5—5 of Fig. 1;

Fig. 6 is a detail sectional view on the line 6—6 of Fig. 2;

30 Figs. 7 and 8 are detail views illustrating other parts of the device.

In the drawings, 10 designates an arched axle mounted in the usual manner upon wheels 11, and secured to the vertical arms of said axle, adjacent their lower ends, is 35 a U-shaped dump-frame 12 whose ends 13 project beyond and in front of vertical arms of the arched axle. This dump-frame 12 is rigidly supported at its rear side by a handle 14 which is secured to said frame by braces 40 15, and whose front end 16 is curved upwardly and forwardly from the rear side of the frame to the top side of the arched axle where it is rigidly secured in position by the U-bolt 17, said front end 16 forming 45 a brace member for the frame, whereby the frame and the arched axle can be tilted up and down by operating the handle 14, the wheel-spindles 18 forming the pivots for the arched axle.

50 Pivotally suspended from the free ends of the frame at 18 by the hanger bars 19 is the scoop or scraper 20, said bars being rigidly secured to the scoop in any suitable manner at a point forward of the vertical center of the scoop, so that, when the scoop is loaded, the preponderance of weight will be in the

back end of the scoop, said back end being supported in loaded position by a latch-member 21 pivoted to the arm 16 slightly to the rear of the rear side of the frame 12. 60 This latch-member is provided with a suitable hook 22 at its lower end, which is adapted to engage a keeper 23 rigidly secured to the rear wall of the scoop, while the latch-member is held in engagement with 65 the keeper by a spring 24.

At the front edge of the scoop, at both sides thereof, are secured the hooks 25, said hooks being open at their under sides and adapted to be engaged by the drag-hooks 26 70 in certain positions of the scoop. These drag-hooks 26 are rigidly secured to the sides of the drag-bars 27, the rear ends of which are pivotally connected at 28 to a frame secured to the axle at points between the 75 arched axle and the pivotal points 18 of the bars 19. The front ends of the drag-bars 27 are inclined toward each other and are secured to the tongue 34, the rear end of which engage over a transverse bar 29 which 80 has its ends supported upon the drag-bars 27 and secured thereto by brackets 30 (see Fig. 6).

It has been found by practical experience 85 that under severe strains of unequal pulling upon the sides of the scoop, due to the twisting of the dragging members attached to the scoop, the front edges of the sides of the scoop become distorted, thus causing unequal loading of the scoop and breaking down of 90 the sides at these front edges. To remedy this defect, a pair of adjustable truss-members 31 is provided, the same being secured to the drag-bars 27 by suitable bolts, and said members 31 are extended inwardly and 95 upwardly from said drag-bars and pass over the tongue 34. Thus it will be seen that the draft-frame, comprising the drag-bars 27, transverse bar 29 and tongue 34, is bound together and maintained rigid and prevented 100 from twisting by the truss-members 31 and the other described connecting means.

The ends of the dump-frame 12 are secured to the axle 10 by the bolts 33 which pass through back-plates 34, and outer plates 36 which cover the outer sides of the portion of the frame 12 lying adjacent thereto. These outer plates 36 project beyond the front sides of the axle to a point adjacent the pivotal points of the hanger-bars 19, and adjacent to the rear edges of each of these plates 36, in a plane below 110

the frame 12, is secured a supporting arm 38 which is slightly bowed outwardly, and between the front end thereof and the plate 36 is pivoted the rear end of the drag-bar 27. These arms 38 on both sides of the scraper are bowed outwardly a sufficient distance to provide a clearance for the drag-bars 27 in the operation of raising and lowering the bucket or scoop, and a spacing-washer 39 is used around the pivot-bolt 28 to maintain the drag-bars 27 free from contact with the outer side of the hanger-bars 19. Stops 40 are secured to the outer sides of the scoop in position to contact with the under sides of the drag-bars 27 when the scoop is raised to the carrying position.

In operation, assuming the parts in the position shown in Fig. 1, the scoop being empty, the front end of the scoop is lowered to scraping position by the attendant walking behind the scoop by releasing the latch-member 21 from engagement with the keeper 23 and lifting the handle 14 to turn the arched axle 10 forwardly and downwardly. This movement throws the scoop forwardly so that its hooks 25 engage the drag-hooks 26; thus a portion of the draft is transferred directly to the front end of the scoop. At the same time, the attendant at the rear grasps the scoop-handle 55 and elevates the rear end of the scoop to cause the front lip or point of pan to bite the earth, as shown in the Fig. 2 position. After a sufficient load has been scraped into the scoop, the attendant grasps the handle 14 and starts to pull down thereof, whereupon the pivotal points of the scoop-hangers 19 rise slightly above the pivotal points of the drag-bars 27, and then the draft animals which are pulling during this portion of the operation not only pull the load through the engagement of the drag-hooks 25 and 26, but also pull upon the axle through the drag-bars 27, and, as the pivotal point 28 has been moved slightly below the plane of the pivotal point 18, the pivotal point 18' of the axle and the wheels are drawn forwardly and tilt the arched portion of the axle backwardly, thereby lifting the scoop from the ground and separating the hooks 25 and 26. In the meanwhile, the attendant is also pulling down on the handle 14, and, when the scoop is raised to the position shown in Fig. 1, the hook of the latch 21 automatically engages the keeper 23 and thus retains the scoop in the elevated position.

It will thus be seen that the draft power almost entirely lifts the loaded scoop to the carrying position, thereby relieving the attendant of this burden.

After the load has reached the dumping ground, the attendant throws the handle 14 upwardly with the latch 22—23 engaged,

thus lowering the front end of the scoop to the ground. At this time, the pivotal points 18 having been lowered with respect to pivotal points 28, due to the dropping of the scoop, the draft power pulls the axle and wheels over and beyond the pivotal points 18, which are substantially stationary owing to the contact of the lip of the scoop with the ground, and, consequently, the rear end of the scoop is lifted and carried over the point of contact of the scoop-lip with the ground, and the load is dumped. In this manner, the draft power dumps the load, and the leverage of the draft with respect to the bucket is such that the dumping operation is easily accomplished with at least one-half the animal power heretofore used.

In the scraping position, to prevent accidental tipping of the scoop and disengagement of the drag-hook 26, a safety-hook 47 is provided whose hook portion is turned in an opposite direction from the hook 26, and said safety-hook 26 is formed on the lower end of an arm 48 pivoted at its upper end to the drag-frame 27. On this arm 48 is rigidly fixed another safety-hook 49 which is adapted to engage the scoop-hook 25 when the scoop is in the carrying position, as shown in Fig. 1 of the drawing. These two safety-hooks are controlled by a rearwardly-extending operating-rod or handle 50, the same being pivoted at its front end to the arm 48 and having its rear end slightly supported by a loop 51 pivotally fixed to the frame 12, said operating-rod being provided with a projecting lug 52 which is adapted to pass through and engage the rear side of the scoop 51 when it is desired to lock the safety-hooks free from engagement with the drag-hooks, especially during the dumping operation. These safety-hooks are only required on one side of the scraper.

A chain 53 is provided for regulating the height of the throw of the frame 12 which carries the handle 14 during the scraping operation. This chain is provided with a ring 54 adapted to engage over one of the scoop-handles 55, and the links at its free end are adapted to adjustably engage in a hook-plate 56 fixed to the frame 12, whereby the chain may be adjusted in length.

The plate 36 is formed with a horizontal portion 57 which overlies the ends 56' of the axle and is secured in place by the bolts 58 which pass through said portion 57 and down alongside the ends 56' of the axle and also through a bottom-plate 59.

To the upper side of the portion 57 of the plate 36 is preferably secured an angular plate 60 which is secured in place by the bolts 58, and to the vertical member of this angular plate 60 is secured a sand-band 61 which surrounds the hub on its inner side.

As a further strengthening means for the draft elements and to prevent twisting and distorting of the parts subjected to the greatest strains, supplemental braces 62 are provided. These braces 62 are secured at one end to the drag-bars 27 by the bolts 63 and from this connection extend inwardly and upwardly and have their other ends connected to the sides of the tongue by the bolts 64.

Drag-bars 27 are preferably reinforced by straps 27' which extend the greater part of their length and are secured at their ends thereto. These straps 27' are spaced from the drag-bars 27 for a portion of their length and in these spaces lie the upper ends of the hooks 48 and 26. Bolts 63 which secure the ends of braces 62 to the bars 27 extend to the outside of the straps, and the ends of the truss-members 31 pass through the bars 27, the upper ends of the hooks 26 and the straps 27' and are secured in position by the nuts 31' on the outside of the straps 27'. It will be observed that the center portions of the truss-members 31 are formed with chains to provide a flexibility to permit the ends of the trusses to be withdrawn from the drag-bars 27 and their reinforcing straps 27', so that the hooks 26 can be removed for repairing or replacement. It will be observed that the pivots 18 and 28 are in different vertical planes in order that they may pass each other in the manner above described.

For nearly all purposes, the upper safety-hook 49 is all that is necessary, but without the use of the lower safety-hook 47, the scraper would be prematurely dumped in the event the cutting-edge of the scraper should rest against a solid obstruction like a stump or rock when the handle 14 is pulled down to bodily lift the load.

What I claim is:

1. In an earth-scaper, an arched axle and wheels, a dump-frame rigidly secured to said axle and extending rearwardly therefrom, said dump-frame having extensions forward of the axle, a scoop pivotally suspended from the front end of said frame extensions, a draft-frame having its rear ends pivotally attached to said axle at a point to the rear of the scoop connections therewith, and cooperating hooks on said draft-frame and scoop adapted to engage with each other in the loading position of the scoop.

2. In an earth-scaper, an arched axle and wheels, a dump-frame rigidly secured to said axle and extending rearwardly therefrom, extensions projecting in front of the axle adjacent its vertical arms, a scoop pivotally suspended from the front end of said extensions, a draft-frame having its rear ends pivotally attached to said axle at a point to the rear of the scoop connections

therewith, and cooperating hooks on said draft-frame and scoop adapted to engage with each other in the loading position of the scoop.

3. In an earth-scaper, an arched axle and wheels, a dump-frame rigidly secured to said axle adjacent its wheel-spindles and extending rearwardly therefrom, extensions projecting in front of the axle adjacent its vertical arms, a scoop pivotally suspended from the front end of said extensions, a draft-frame having its rear ends pivotally attached to the axle in a manner to cause its pivotal connections to lie below the plane of the pivotal connections of the scoop in load-carrying position and as the scoop is raised toward dumping position to move to a plane above the scoop connections, and cooperating hooks on said draft-frame and scoop adapted to engage with each other in the loading position of the scoop.

4. In an earth-scaper, an arched axle and wheels, a dump-frame rigidly secured to said axle and extending rearwardly therefrom, extensions projecting in front of the axle adjacent its vertical arms, a scoop pivotally suspended from the front end of said extensions, means for latching said dump-frame and scoop together, a draft-frame having its rear ends pivotally attached to said axle at a point to the rear of the scoop connections therewith, and cooperating hooks on said draft-frame and scoop adapted to engage with each other in the loading position of the scoop.

5. In an earth-scaper, an arched axle and wheels, a dump-frame rigidly secured to said axle and extending rearwardly therefrom, extensions projecting in front of the axle adjacent its vertical arms, a scoop pivotally suspended from the front end of said extensions, a draft-frame having its rear ends pivotally attached to said axle to the rear of the scoop connections therewith, cooperating hooks on said draft-frame and scoop adapted to engage with each other in the loading position of the scoop, and a safety-hook pivoted to said draft-frame adapted to engage the hook on the scoop to prevent accidental tilting of the scoop when being carried in a loaded position.

6. In an earth-scaper, an arched axle and wheels, a dump-frame rigidly secured to said axle and extending rearwardly therefrom, extensions projecting in front of the axle adjacent its vertical arms, a scoop pivotally suspended from the front end of said extensions, a draft-frame having its rear ends pivotally attached to said axle to the rear of the scoop connections therewith, cooperating hooks on said draft-frame and scoop adapted to engage with each other in the loading position of the scoop, and a pair of safety-hooks pivoted to said draft-frame and successively adapt-

ed to engage the hook on the scoop to prevent the accidental tilting of the scoop in either carrying or loaded position.

7. In an earth-scraper, an arched axle and 5 wheels, a dump-frame rigidly secured to said axle and extending rearwardly therefrom, extensions projecting in front of the axle adjacent its vertical arms, a scoop pivotally suspended from the front end of said 10 extensions, a draft-frame having its rear ends pivotally attached to said axle to the rear of the scoop connections therewith, cooperating hooks on said draft-frame and scoop adapted to engage with each other in 15 the loading position of the scoop, a pair of safety-hooks pivoted to said draft-frame and successively adapted to engage the hook on the scoop to prevent the accidental tilt-

ing of the scoop in either carrying or loaded position, and a locking control handle for 20 said safety-hooks.

8. In an earth-scraper, an axle and wheels supporting the same, a dump-frame secured to said axle, a scoop pivotally supported by the dump-frame, a draft-frame pivotally 25 secured to the axle, the pivotal points of said scoop and drag-frame being arranged in different vertical planes and so positioned as to change their horizontal planes with respect to each other and alternately one 30 above the other when the dump-frame is manipulated to tilt the axle back and forth.

In testimony whereof I hereunto affix my signature.

JAMES M. BROOKS.
